UNITED STATES PATENT OFFICE.

CURTIS M. CLAYPOOLE AND ALVIN J. ESHENBAUGH, OF BUTLER, PENNSYLVANIA.

CASING COUPLER.

Application filed September 5, 1925. Serial No. 54,834.

This invention relates to a casing coupler, or device for use in connecting together two disconnected or broken parts of a well casing, whereby the casing in entirety may be removed from the well.

One object of the invention is to provide a simple, inexpensive and easily operated type of coupler adapted to be lowered into the casing and which is provided with gripping devices adapted to firmly and securely grip and couple the casing sections against any possibility of slipping, and whereby the casing sections may be positively and rigidly coupled for conjoint removal from the well.

Another object is to provide spring-actuated grippers to engage the upper section of the casing and a locking device for holding said grippers normally retracted and for releasing them for action, said locking device being releasable from the coupler by proper manipulation of the drill cable to permit said grippers to set and also to permit the drill tools and cable to be removed from the well and out of the way, so that the casing may be extracted without interference therefrom.

Still another object of the invention is to provide a locking device which may also be used as a connector and releaser for engagement with the casing coupler, whereby the lowered and set coupler may be released and pulled out of the casing in the event that it is found that the casing can not be extracted, or it is desired to release and remove the set coupler for any other cause.

Still another object of the invention is to provide a coupler which effectually obviates the necessity of cutting the drill cable at any point, and avoids the possibility of the loss of the drilling tools or any portion of the cable, and which, furthermore, permits of the removal of the casing sections joined thereby through power applied directly to the upper casing section and not to the coupler.

Still another object of the invention is to provide a construction of spear carrying lower slips or grippers adapted for an automatic setting action and which are retractable for a releasing action when it is desired to release and remove the coupler from the well casing.

With these and other objects in view, the invention consists of the features of con-

struction, combination and arrangement of parts, hereinafter fully described and claimed, reference being had to the accompanying drawings, in which:—

Figure 1 is a side elevation of the coupler as arranged for downward movement in a well casing, the latter appearing in section.

Figure 2 is a view of the parts shown in Figure 1 looking at the same from a position at right angles to Figure 1.

Figure 3 is a vertical longitudinal section through the coupler fitted in position between two separated portions of a well casing and as arranged just prior to being set or fixed to the well casing sections.

Figure 4 is a view similar to Figure 3 showing the coupler set to couple the well casing sections together for a pulling action.

Figure 5 is an enlarged horizontal transverse section on line 5—5 of Figure 3.

Figure 6 is a similar view on line 6—6 of Figure 3.

Figure 7 is a similar section on line 7—7 of Figure 3.

Figure 8 is a similar section on line 8—8 of Figure 3.

Figure 9 is a sectional view through the upper coupler section or member.

Figure 10 is a sectional view through the intermediate, positioning or stop member section of the coupler.

Figure 11 is a view of the locking and releasing plunger applied for clutch connection with the upper coupler section or member.

The device comprises a body which, for convenience, may be made in several sections adapted to be detachably coupled together, said device being shown in the present instance as embodying an upper or coupler section A, an intermediate positioning or stop section B and a lower coupler or spear section C. Provided for cooperation with these parts, constituting the coupler per se, is a locking and releasing device D.

The upper coupler section or member A is provided with a longitudinal bore 1 extending from end to end thereof, the lower end of said bore being formed to provide a threaded socket 2 receiving a threaded stem 3 on the upper end of the member B, whereby said members are adapted to be detachably connected. The member A is formed with a socketed upper end 4 and has two

of its diametrically opposite sides provided with flattened faces 5 converging in a downward direction and extending between the lower portion of the part 4 and shoulders 6. The flattened, inclined faces 5 give a desired taper to the intermediate portion of the member A in one diametrical direction, and said faces 5 form slideways for segmental grippers or slips 7, provided with dove-tailed guide ribs 8. These dove-tailed guide ribs 8 slidably engage grooved guideways 9 formed in the sides 5 and extending at a corresponding angle of inclination thereto between the reduced portion 4 and the shoulders 6. The grippers 7 normally rest at their lower ends upon the shoulders 6, by which their downward movement is limited, and when so disposed the grippers are in retracted position. The grippers are connected for sliding movement in unison by a cross pin or key 10 extending transversely across the bore 1 and through guide slots 11 intersecting the grooves 9, which pin or key by engagement with the upper walls of the slots limits the upper movement of the grippers. The grippers are movable upwardly and outwardly on the inclined faces to project them for gripping engagement with the pipe casing, and the outer surfaces of said grippers are provided with downwardly projecting gripping teeth 12 to impinge against the casing and firmly lock the grippers and the coupler section A thereto. The grippers are adapted to be inserted in position via the upper ends of the grooves 9 and are then connected and held in position by fitting the pin or key 10 in place.

A coiled expansion spring 13 is fitted in the lower portion of the bore 1 and is arranged to bear at its upper end against the pin or key 10 and at its lower end against the abutment formed by the stem 3, said spring exerting its expansive force on the pin or key 10 to slide the grippers 7 upwardly on the inclined faces 5 to project them for gripping position.

The positioning or stop member B comprises a body 14 formed at its lower end with an internally threaded socket 15 to receive a threaded plug or stem 16 on the upper end of the spear member C, whereby said members are detachably coupled together. Formed in the opposite sides of the body 14 are recesses 17 receiving a pair of locking dogs 18 pivotally mounted at their upper ends, as at 19, within said recesses, so that their lower portions may swing within the recesses and outwardly and inwardly beyond and within the plane of the body 1. Springs 20 are provided in the body 14 to bear against the lower ends of the dogs to normally hold the same projected, in which projected position the lower ends 21 of the dogs form stop shoulders for engagement with the upper end of a lower casing section E to

be joined to an upper casing section F by the coupler, as hereinafter described. The outer edges of the dogs incline in an outward and downward direction to properly shape the dogs for provision of the shoulders 21 and to provide beveled surfaces whereby the dogs are adapted to recede when the coupler is drawn upwardly in the casing, to prevent any interference on their part with such upward movement.

The lower coupler section or member C as shown in the present instance comprises a spear formed of any suitable number of parts and having at its upper end a threaded projection 16 for detachable engagement with a socket 15 in the lower end of the member B. This spear section is provided with slip grippers 23 having toothed outer faces 23^a, the teeth of which project upwardly. These grippers are similar in construction to the grippers 7, having flattened guide faces at their inner sides provided with dove-tailed ribs engaging dove-tailed guide grooves formed in inclined sides 24 of the member C, which is slotted transversely to receive and permit of the sliding movement of a cross bar 24^a connecting said grippers, the construction of the part C for the mounting of the grippers being similar to that of the member A. A coiled expansion spring 25 contained in the member C is arranged to normally bear at its upper end against the bar 24^a to hold the grippers 23 normally at the limit of their upward movement, or in retracted position. Formed in the sides of the section C, at right angles to the inclined faces 24, are diametrically disposed bores receiving guide sleeves 26 terminating at their outer ends a distance inwardly of the outer ends of said bores and projecting at their inner ends partially into the slot or passageway in which the bar 24^a slides. These sleeves 26 receive locking pins 27 having headed outer ends 27' to engage the outer ends of said sleeves, whereby the inward movement of the locking pins is limited. Springs 28 are provided in the sleeves to normally hold the pins projected with their headed ends in contact with threaded plugs 28' closing the outer ends of the bores. When the pins are held retracted their inner ends project a slight distance inwardly to lie out of the way of the coils of the spring 25, allowing said spring to have free expanding and contracting movements without interference therefrom. By means of these locking pins the spring 25 may be held compressed and out of engagement with the slips 23, to allow said slips to have a limited up and down motion without a setting action, in order to adapt the spear member to be lowered into the well casing and adjusted for a gripping action. In adjusting the pins for this locking action, which is effected prior to the application of the member C

to the member B, the plugs 28' are removed, the grippers 23 forced downwardly in any suitable manner until the upper end of the spring 25 comes below the pins 27, the said 5 pins then forced inwardly against the resistance of their retracting springs until their inner ends lie between the upper end of spring 25 and the cross bar 24^a, after which the plugs 28' are inserted, the pins 10 being held from retraction in said locking position by frictional and clamping engagement between the spring 25 and the bar 24^a. The member C is then in condition to be lowered into the well casing with the grippers 23 free for a certain range of movement and in readiness to be projected for a gripping action on the lower section of the well casing in the manner hereinafter described.

The member D constitutes a locking and 20 releasing plunger element, which is adapted for application to the coupler member A to compress the spring 13 and force the grippers 7 downwardly to retracted position. At its upper end the part D is provided with a 25 threaded stem or plug 29 for engagement with a threaded socket 30 in the drill jar or head 31 to which the drill tools and cable are connected, whereby, through the member D, the coupler body may be attached to the drill 30 rigging for lowering, positioning and casing gripping actions, and for the subsequent release of the member D from the coupler body, whereby the grippers 7 may be automatically unlocked and released for action 35 and the drill cable, jar and tools left free to be withdrawn from the well casing. The member D is properly shaped to enter the socket 4 and is provided with a plunger portion or stem adapted to be received in the 40 upper portion 33 of the bore 1 of the member A and to engage the locking pin or key 10 and compress the spring 13 and force the grippers 7 downwardly to a full retracted position. When such portion 32 of the member D is fully inserted in the bore portion 45 33, a transverse opening 34 in the plunger 32 is brought into alignment with a similar opening 35 in the member A, which openings 34 and 35 are adapted for the reception 50 of a connecting pin or key 36, whereby the member D is fastened to the member A to couple the latter to the drill cable and depressed to hold the grippers 7 locked in retracted position, in which position the device 55 as a whole may be lowered into the well tubing without interference from said grippers. The pin or key 36 is of a size and material to make it of sufficient strength for the connecting action referred to, but is 60 weak enough so as to be breakable under upward pull or jars upon the cable when the coupler is set rigidly to the well sections by the upper and lower sets of grippers, so that a ready release of the plunger-like locking and releasing member D from the set 65

coupler may be effected; to permit it and the drill cable and tools to be withdrawn from the well casing.

The member D is slotted and provided with inclined side faces, similar to members 70 A and C, for the reception, when desired, of small slips or grippers 37, which are freely slideable up and down on said inclined faces. The pin or cross-bar 38 connecting these grippers is of detachable type to allow the 75 grippers to be readily applied and removed. The portion of the member D carrying said grippers, which are arranged above the plunger portion thereof, is adapted to enter the enlarged upper portion or socket 4 of 80 the member A and have a sufficient extent of movement therein for a downward movement of its plunger portion to release the grippers 7 and a subsequent upward or recessive movement for setting the grippers 85 37. The grippers 37 are designed to be applied to the member D whenever it is desired to effect the release of the coupler from the well casing, and its extraction therefrom, after the coupler has been set and it 90 has been found by test that the casing sections can not be pulled out of the well, and the recovery of the coupler is desired.

In the operation of the device, the members A, B and C and their parts are properly 95 assembled for use with the grippers 23 locked in retracted position by the pins 27 as previously described, and then the members B and C are inserted into the top of the well casing, the dogs 18 being forced inwardly in any suitable manner to permit of their introduction, after which the device is suitably suspended in the top of the well casing with the member A projecting 100 while the locking and releasing member or plunger D is being applied and fastened with the drill jars to the drill cable. In this operation of applying the member D, it is lowered by means of the drill cable mechanism so that its lower end will properly 105 pass down into the bore of the member A and engage the pin 10 and depress the grippers 7 until the openings 34 and 35 come into register, after which the pin 36 is inserted to hold the parts connected in such position. 110 This downward movement of the member D, is assisted by the weight of the drill jar and tools, which is sufficient to overcome the resistance of the spring 13, so that a ready application of the member D to the member A 115 will be secured. When this operation is completed, the coupler, with the grippers 7 and 23 retracted, is in readiness to be lowered into the well casing by means of the drill cable and drill mechanism and will descend by gravity until the dogs 18 reach the space between the separated ends of the upper and lower casing sections 37 and 38, whereupon the dogs will spring outwardly 120 and their shoulders 21 will engage the upper 125 39 and hold the sections together.

end of the lower casing section 38 and hold the coupling device from further downward movement and in proper position for the grippers 7 and 23 to engage the casing sections 37 and 38, respectively, as shown in Figure 3. When this position is reached, a slight upward pull upon the draft cable will move the body of spear C upward sufficiently to project and set the lower grippers 23, as shown in Figure 4, thereby coupling the lower member or spear C to the lower pipe section 38, preventing further upward movement of the coupling device within the casing. By now exerting a continued upward pull on the cable or by producing shocks or jars as a result of sudden, sharp pulls on the drill cable, sufficient strain may be placed upon the pin 36 to fracture it, thus disconnecting the member D from the member A, freeing the member D, the drill tools and the cable for withdrawal in entirety from the well casing. The withdrawal of the member D, resulting in the removal of pressure from the spring 13, allows the spring 25 to act to force the grippers 7 into engagement with the upper casing section 37, whereby the coupler will grip the lower and upper casing sections above and below the point of break and will fasten them firmly for conjoint removal, which may be effected by direct pulling power applied to the casing from above in the usual way, the coupler when thus applied accordingly acts merely as its name implies, a fastening connecting the separated well casing sections for removal in unison, avoiding the necessity of attempting to pull the casing out of the well by power applied to the coupling itself, under which it is liable to break. By the provision of the locking and releasing plunger D, and its fracturable fastening connection 36, ready and easy adjustment of the drill tools and drill cable from the well may be effected and leaving the well free and clear of interfering objects in its removal. Our invention, therefore, obviates the necessity of employing means for cutting the cable after the coupler is set, either at or below the surface, which in many cases is impossible and in others can not be effected without great trouble and difficulty, and without the liability of the loss of the drill tools and expensive amount of cable.

In the event that it is found that the well casing can not be withdrawn from the well, after the coupler has been lowered and set to connect the disconnected sections thereof, extraction and recovery of the coupler is desirable. This may be effected as follows. As shown in Figure 4, the upward movement of the coupler in the well casing, whereby the grippers 7 and 23 are set, results in the raising of the dogs 18 above the upper end of the lower casing section E, whereby a determined downward movement of the coupler

as a whole in the well casing is permissible. By now applying drill tools or weights to a drill jar fastened to a drill cable, these may be lowered into the well and operated to exert hammer blows on the socket 4, whereby the coupler may be forced downward into the casing until the dogs 18 again engage the upper end of the casing section E. This action will result in the grippers 23 being forced upward and the locking pins 27 jarred out of locking position by vibrations of the spring 25, said pins being retracted by their springs 28, thus freeing spring 25 so that it will force the grippers 23 upward to a fully retracted position and thereby release the spear from engagement with the casing section E. When this is done the section D, fastened to the drill cable, and to which the jaws 27 are applied for use, is lowered into the well casing so that it will enter the socket 4 and so that its plunger portion 32 will engage the cross-bar 10 and force the spring 13 downward to permit retraction of the grippers 7. In this operation the grippers 37 enter the socket 4 and permit downward movement of the member D therein to the fullest extent, but, on a slight upward pull of the cable, the grippers 37 will engage the wall of the socket 4 and become set, thereby coupling the member D to the member A. This upward movement of the member D to set the grippers 37 will be within a range in which plunger 32 still holds the spring 13 depressed so that the grippers 7 will still remain retracted. Both sets of grippers 7 and 23 will thus be in released position, allowing the coupler to be pulled out of the well. By proper manipulation the grippers 37 may then be released from the member D, restoring the coupler in condition for further use.

If desired hooks, grapples or other devices may be applied to the coupler in lieu of the spear C, whenever it is desired to fish a well casing for the recovery of tools or other articles falling thereto, thus increasing the range of usefulness of the device.

Having thus fully described our invention, we claim:

1. A coupler of the character described comprising a body having a central longitudinal bore and a cross passage intersecting said bore, sliding grippers at opposite sides of the body, a cross piece in said cross passage and connecting said grippers, a spring acting on said cross piece for projecting the grippers, a member adapted to be attached to a cable and having a plunger pin adapted to be fitted in said bore and engaged with the cross piece for exerting pressure thereon to hold the grippers retracted, and a fracturable pin for directly connecting said plunger with the coupler body.

2. A coupler of the character described having automatically projectable grippers,

a member adapted to be attached to a manipulating cable and to be engaged with the coupler to hold the grippers retracted, means for fastening said member to the coupler, 5 said means being releasable by pulls or jerks on the cable to free said member and cable for withdrawal from the well casing, and means applicable to said member whereby it may be re-engaged with the coupler and 10 interlocked therewith.

3. A coupler of the character described comprising a coupler body, stop means on the coupler body, upper and lower grippers on the coupler body, a member adapted for engagement with the coupler body to effect the release of the upper grippers, a releasable connection for connecting said member with said coupler body, said connection being releasable under pulls or jerks upon said member, and means independent of said connection for automatically connecting said member with said coupler body by movement of said member into engagement with said coupler body. 20

25 4. A coupler of the character described having spring-actuated upper gripping jaws, spring-actuated lower gripping jaws, stop means between said jaws, locking means for holding the lower jaws from action while permitting such jaws to have a certain range of setting movement, said locking means being rendered inoperative by a forcible downward movement of the coupler, a member engageable with the coupler to hold the upper 30 jaws retracted, means for releasably connecting said member with the coupler, said means being operative for a releasing action by pulls or jerks upon said member, and means applicable to said member for automatically 35 interlocking the same with the coupler when said member is moved into engagement with the coupler.

5. In a coupler of the character described, a coupler body, grippers on the coupler body, 40 a member adapted to be engaged with the coupler body to hold the grippers retracted, and slip grippers on said member for automatically locking the same to the coupler body on being brought into engagement therewith.

55 6. A coupler of the character described having automatically projectable grippers, a member adapted to be attached to a manipulating cable and to be engaged with the coupler to hold the grippers retracted, means for fastening said member to the coupler, said means adapted to be fractured by pulls or jerks on the cable to free said member and cable for withdrawal from the well casing, 60 and means applicable to said member whereby it may be reengaged with the coupler to release the projected grippers and locked to the coupler so that the released coupler may be withdrawn from the well.

65 7. A coupler for connecting two sections

of a well casing comprising a body having upper and lower pairs of oppositely disposed inclined faces, a cross passage between the upper inclined faces, and a bore extending downwardly from the upper end of the body 70 and intersecting said passage, lower gripping members slidable on the lower inclined faces of the body and adapted for engagement with the lower pipe section, said members being automatically retractable on the 75 downward movement of the coupler and adapted to be set on an upward movement thereof, upper grippers slidable on the upper inclined faces of the body and adapted for engagement with the upper casing section, a cross piece on said cross passage connecting the upper grippers, a spring acting on said cross piece for automatically projecting said upper grippers, a member adapted to be attached to a cable or the like and 80 having a plunger pin adapted to be inserted into said bore and to press upon the cross piece to hold the upper grippers normally retracted against the pressure of their actuating spring, and a fracturable locking pin 85 for connecting said plunger pin to the coupler body, said locking pin adapted to be fractured by pulls or jerks upon the cable to effect the release of said member from the coupler body and the withdrawal of the same 90 with the cable from the well.

8. A coupler of the character described having automatically projectable gripping means, a member adapted to be coupled to a drill cable and to be engaged with the coupler to hold the gripping means from action, a fracturable connection for holding said member applied to the coupler, and automatic gripping means carried by said member for a grip lock connection between the 105 same and the coupler.

9. A coupler of the character described comprising a coupler body, stop means on said coupler body, automatic gripping means on said coupler body, a member adapted for engagement with the coupler body to release said gripping means, and automatic gripping means on said member whereby the same may be locked to the coupler body. 110

10. A coupler of the character described comprising a coupler body, stop means on the coupler body, upper and lower grippers on the coupler body, a member adapted for engagement with the coupler body to effect the release of the upper grippers, a fracturable pin for normally connecting said member with said coupler body, and gripping means adapted to be applied to said member for a grip-lock between the same 120 and the coupler body.

11. A coupler of the character described having spring-actuated upper gripping jaws, spring-actuated lower gripping jaws, stop means between said jaws, locking means for engagement with the actuating spring of 130

the lower jaws for normally holding said spring from action while permitting the jaws to have a certain range of setting movement, said locking means being rendered 5 operative by a forcible downward movement of the coupler, and a member engageable with and disconnectible from the coupler

and operative when engaged with the coupler to hold the upper jaws retracted.

In testimony whereof we affix our signatures.

CURTIS M. CLAYPOOLE.
ALVIN J. ESHENBAUGH.
